CAKE FLEXING MACHINE

Donald C. Thompson, Roanoke, Va., assignor to
 American Viscose Corporation, Wilmington,
 Del., a corporation of Delaware

Application February 5, 1942, Serial No. 429,617

6 Claims. (Cl. 18—8)

This invention relates to a device adapted to flex and to thereby somewhat loosen rayon cakes such as are produced in the centrifugal bucket spinning processes preparatory to treating them with liquids.

It is an object of the invention to flex the rayon cakes, preferably a plurality, simultaneously, without injuring the filaments in them. A further object is to provide a machine for automatically flexing such cakes while they are being conveyed from one stage of manufacture, such as the cake-wrapping step, to a second stage of treatment such as the cake-washing, desulfiding, and other liquid treatment stages. A further object is to effect the flexing with contacting surfaces moving at the same speed as the cakes. A further object is to provide a flexing device arranged in a manner with respect to the conveyor such that uniform flexing of each cake is obtained. Further objects will appear from the drawing and the description thereof hereinafter.

The single figure of the drawing is a perspective view of the cake flexing device showing its relation to the conveyor.

In the figure, the cakes 2 are supported by rods 3 whose ends are set within the notched brackets 4 fixed upon the carrier 5 which is pivoted to the hanger 6 pivotally connected at 7 to the conveyor chain 8. The hanger is provided with a yoke 9 and the rollers 10 which ride within the guide-ways 11 provided by the I-beam track 12. This track is suitably suspended from overhead beams or from the ceiling of the plant and acts as a guide for the chain conveyor to conduct the cakes from one stage of handling, such as the cake-wrapping stage, to a second point of handling, such as the liquid-treatment stage. The cakes, as they are wrapped, are put upon the rods 3, each rod supporting as many as may fit along its length, and the loaded rods are then put into the carrier 5 shown. The carrier may support any number of such rods, two being shown in the drawing. The rods are preferably arranged horizontally so that the cakes are not weighted non-uniformly during the flexing treatment. The conveyor chain 8 is provided at intervals with hangers and carriers and moves them continuously in a circuit from the wrapping point to the liquid treatment point and, after unloading, back to the wrapping point.

After the carriers have been loaded, the continuously moving conveyor brings them through the cake flexing device shown in the drawing which is supported within the framework 13 suspended from the ceiling or beams overhead.

This framework supports a suitable driving mechanism, such as the motor 14, which by means of the two sprockets 15 and 16 on its shaft 17 is adapted both to drive the chain conveyor 8 and to operate the cake-flexing device. Every fifth link of the driving chain 18 operated by sprocket 15 is provided with an outwardly protruding lug 19 adapted to engage with the links of the conveyor chain 8. A second sprocket 20 supported on the shaft 21 is arranged so that one course of the driving chain 18 operates in a line parallel and closely adjacent to the conveyor chain 8 so that the lugs 19 effect the continuous driving desired. Within the framework, there are supported two pairs of shafts 22, 23 and 24, 25, one pair being provided with the rollers 26 and 27, and the other pair being provided with the belt driving rollers 28 and 29, which, as shown in the drawing, are of larger diameter than the idler rollers. A pair of belts 30 and 31 are driven upon the opposite rollers of each pair. Any suitable driving mechanism may be employed for driving these two belts. As shown in the drawing, the shaft 25 is provided with a sprocket 32 which is driven from the sprocket 16 by means of the chain 33. The shaft 24 carrying the other driving roller 28 is driven through the sprocket 34 thereon, the chain 35 connecting it to a second sprocket 36 fixed to the shaft 31 to which is secured a gear 38 in mesh with a second gear 39 upon the shaft 25. Whatever the driving mechanism selected, the gear ratios and sprocket sizes should be chosen so that the two belts 30 and 31 move in the same direction at substantially the same speed as the conveyor chain 8 so that there is no tendency for the belts to force the cakes against the upright ends of the carrier 5 as they proceed through the device. The belts and the rollers about which they run are so arranged that their opposed courses converge in their direction of travel, sufficient space being allowed between their closes approach to permit free passage of the carrier itself therebetween.

After the cakes are compressed by passage between the two belts, the conveyor 8 conducts the cakes on the carrier 5 to the charging station of any suitable apparatus, such as the liquid treatment apparatus shown in the patents to Allen et al., 2,200,197 at which point the flexed cakes, with or without the rods, are transferred from the carriers to the liquid treatment machine.

While a preferred embodiment of the invention has been disclosed, the description is intended to be illustrative only, and it is to be understood that changes and variations may be made with-

out departing from the spirit or scope of the invention as defined by the appended claims.

What I claim is:

1. A device for altering the shape of annular, wound packages comprising two belts arranged with their opposed courses forming a channel therebetween converging from a span at least about as large as the diameter of the packages to a span substantially less than the package diameter, means for driving said belts in the direction of convergence, and means for introducing the packages into the larger end of the channel with their axes extending generally in the direction of convergence of said channel. 15

2. A device for altering the shape of annular, wound packages comprising a carrier, means on said carrier for supporting the packages with their axes substantially horizontal, a pair of opposed pressure members arranged to form a generally vertical channel converging in a generally horizontal direction from a span at least about as large as the diameter of the packages to a span substantially less than the package diameter but sufficiently large to permit free passage of the carrier itself, and means for moving said carrier and cakes between said members in the direction of convergence. 20

3. A device for altering the shape of annular, wound packages comprising two belts arranged with their opposed courses forming a channel therebetween converging from a span at least about as large as the diameter of the packages to a span substantially less than the package diameter, means for driving said belts in the direction of convergence, and means for introducing the packages into the larger end of the channel with their axes extending generally in the direction of convergence of said channel and for conveying them therebetween at substantially the same speed as the speed of the belt. 25

4. A device for altering the shape of annular,

wound packages comprising two belts arranged with their opposed courses forming a channel therebetween converging from a span at least about as large as the diameter of the packages to a span substantially less than the package diameter, means for driving said belts in the direction of convergence, means for introducing the packages into the larger end of the channel with their axes extending generally in the direction of convergence of said channel, and a driving connection between the package introducing means and the belt driving means arranged to convey the packages at substantially the same speed as the belts. 30

5. A device for altering the shape of annular, wound packages comprising a carrier comprising a shallow frame and a plurality of approximately parallel rods supported on the frame in a common plane, two belts arranged with their opposed courses forming a channel therebetween converging from a span at least about as large as the diameter of the packages to a span substantially less than the package diameter but sufficiently large to permit free passage of the carrier itself, and means for moving said carrier between said belts in the direction of convergence. 35

6. A device for altering the shape of annular, wound packages comprising a carrier comprising a shallow frame and a plurality of approximately parallel rods supported on the frame substantially horizontally in a common substantially vertical plane, two belts arranged with their opposed courses forming a vertical channel therebetween converging in a generally horizontal direction from a span at least about as large as the diameter of the packages to a span substantially less than the package diameter but sufficiently large to permit free passage of the carrier itself, and means for moving said carrier between said belts in the direction of convergence. 40
